PULP MOLDING METHOD AND APPARATUS
Ammon M. Leitzel, Portland, Oreg., assignor to Pacific
Pulp Molding Company, Portland, Oreg., a corpora-
tion of Washington
Filed Oct. 2, 1956, Ser. No. 613,475
6 Claims. (Cl. 162—220)

The present invention relates to a method and apparatus for molding pulp articles. The invention is concerned with suction molding of generally planiform articles such as egg flats, fruit trays, plates, compartmented serving trays, cushion flats, packing pads and the like, all of which are of considerable width and breadth compared to any variations in depth. Such articles usually have projections above, and depressions below, a median plane, particularly those used for packing eggs or fruit or as cushioning member. In the formation of such articles a suction mold is employed, there usually being a plurality of such molds mounted upon a large wheel, or upon a chain or other mechanism, whereby each of the molds is successively dipped into a slurry tank and a layer of pulp deposited thereon by suction applied through the mold, the layer being maintained upon the surface of the mold until sufficiently dried to permit its removal from the mold without being torn apart or deformed.

The present invention is concerned with the formation of articles of this character which have substantially smooth surfaces, without the employment of expensive mating dies. Mating dies are usually employed for the purpose of compacting the pulp and smoothing the exposed surface of the layer of pulp on the suction molds, and are usually heated so that drying may be accomplished while the article is undergoing an ironing effect. Not only are such mating dies expensive, since they must be accurately formed and rigid, but they must be applied accurately to the surface of the article and maintained in registry with the suction mold for a considerable period of time. Usually, these requirements are met by a complicated machine employing a number of mating dies. The present invention is distinguished therefrom by the use of a single mating die which is applied to the article for a short period of time, and which is so inexpensive that it may be discarded and replaced if a defect should develop in the mating die. This single mating die is resiliently forced against the exposed surface of the article while it is maintained by suction on the suction mold, for a short period of time immediately succeeding the deposit of the pulp layer on the suction mold. Thereafter substantial drying of the article is accomplished, not only by direct radiation but by the drawing of heated air through the article, rapid drying being thus accomplished.

When molded pulp articles are formed upon suction molds, the outer surface of the layer of pulp initially presents a rough or uneven appearance because the distribution of the pulp fibers on the mold is not entirely uniform, and also because a considerable number of the outer fibers are oriented at a large angle with respect to the outer surface of the layer of pulp. The mating dies force these fibers into the plane of the article and iron out the irregularities in the surface of the article, and also compact the entire article to some extent. The present invention accomplishes these results much more rapidly than by any method or mechanism heretofore known.

In accordance with the present invention, the mating die comprises a substantially rigid, but slightly flexible die member. The mating die member can be manufactured of thin sheet metal, plastics, and other suitable materials, provided that the material has sufficient flexi-

2

bility and durability to be centrally bowed from a slightly concave condition to a slightly convex condition successively in rapid order for many hours of operation, and at the same time have sufficient rigidity to accomplish its function. One suitable material is a glass-fiber reinforced polyethylene plastic such as is commonly used for boat hulls, automobile bodies and the like, the member being built up to a thickness of about one-eighth of an inch for molding a planiform article of about 12 by 20 inches and having projections rising above, and depressions below, its median plane to an extent of about three quarters of an inch in each direction, such as a fruit tray. Such a mating die, when clamped around its periphery in a rigid frame will sustain the weight of a grown man without perceptible deflection, but when fluid pressure in the order of ten to twenty pounds per square inch is applied to its surface it will flex to a position of concavity or convexity, with its maximum deflection at the center being in the order of one-quarter to three eighths of an inch in either direction. Mating dies formed of this material can be so flexed from one extreme to the other a number of times per minute constantly for days on end without failing due to fatigue. Such a member may be quickly formed upon a master mold and is so inexpensive that it may be replaced during normal maintenance shutdowns rather than to chance having it fail during an operating period. A member formed of polyethylene plastic of the same type and dimensions as that described above, without the glass fiber reinforcing therein, has also proven to be satisfactory.

The present invention is illustrated and described in conjunction with a molding machine of the character described and claimed in my copending application Serial No. 547,713, filed November 18, 1955, but it will be readily apparent that the invention may be employed in conjunction with any suitable suction molding apparatus.

It is therefore a principal object of the present invention to provide improved pulp-molding apparatus for forming molded pulp articles having smooth surfaces.

Another object of the invention is to provide pulp molding apparatus of the suction molding type in which molded pulp articles are smoothed and compacted without the employment of expensive, rigid mating dies and mating die application mechanism.

Another object of the invention is to provide pulp molding apparatus of the suction molding type in which a substantially rigid, slightly flexible, mating die member is employed to compact and smooth the molded pulp article.

A further object of the present invention is to provide a method for forming compacted and smooth surfaced molded pulp articles.

Other objects and advantages will appear in the following description of a preferred embodiment of the invention, taken in conjunction with the accompanying drawings, and in which like numerals refer to like parts throughout.

In the drawings, FIG. 1 is an end view, partially broken away in vertical section, and with certain parts of the machine omitted for clarity, of a suitable machine upon which to practice the present method, greater details of which may be ascertained from the above-mentioned copending application, and illustrating the mechanism of the present invention.

FIG. 2 is a partial plan view taken substantially along line 2—2 of FIG. 1.

FIG. 3 is an enlarged vertical section taken substantially along line 3—3 of FIG. 2, illustrating the mechanism at the instant of application of the mating die member to the layer of pulp on the suction mold immediately after it has emerged from the slurry tank.

FIG. 4 is a view similar to FIG. 3 illustrating the removal of the mating die member from the layer of pulp on the suction mold; and

FIG. 5 is a schematic diagram of a control circuit for the means effecting the application and removal of the mating die member.

In the drawings the numeral 10 generally refers to a continuous molding wheel comprising a plurality of peripherally disposed suction molds 12. The molding wheel has a hollow hub portion 14 which is provided with suitable axle extensions (not shown) whereby the wheel is mounted for rotation about a horizontal axis. Such rotation can be produced in any desired manner, for example, as illustrated and described in the above identified application.

A slurry tank 16 is provided, into which a pulp slurry is introduced through any suitable conduit such as the conduit 18. The suction molds are successively dipped into the slurry in tank 16 and then withdrawn therefrom, suction being applied through each of the suction molds while in the slurry so as to cause the deposit of a layer of wet pulp thereon.

The molds 12 are secured at their edges to support elements 20 at the periphery of the wheel 10, the support elements being mounted on the outer ends of radially extending spokes 22 which extend from flanges 24 at the opposite ends of the hollow hub 14. Each of the molds 12 comprises a back plate 26 and a separable mounting rim 28, the two members 26 and 28 being secured together and attached to the support elements 20 by means of studs 30. The member 28 is provided with an opening of substantially the size of the article to be molded and is provided with a peripheral ledge 32 upon which is mounted a perforated, rigid mold 34 forming the principal element of the suction mold. The element 34 is covered by a closely matching screen 36, the periphery of which is clamped to the mounting plate 28 by a peripheral clamp frame 38 and a plurality of studs 40. The screen is of such fine mesh as to prevent the passage of fibers therethrough, but permits substantially uniform suction to be applied to the slurry. When the suction mold is immersed in the pulp slurry a suction valve 42 in its base is opened to permit withdrawal of water through a suction outlet 44.

The interior of the hollow hub 14 is maintained under vacuum at all times. Suitable connection between the hub and a vacuum pump is provided by any of the usual means, such as disclosed in the above-identified application. The conduits 44 from the suction molds are connected to water collection drums 50 mounted within the periphery of the wheel. Each collection drum 50 is connected by a conduit 52 and a valve chamber 54 to the interior, or suction chamber 56, of the mold 12 which is one step forwardly of such collection chamber in the direction of rotation of the wheel 10. Each valve chamber 54 mounts the valve 42 of such mold, the valve being urged toward closed position by a spring 57. The valve 42 for each suction mold is opened at an appropriate time by valve actuating mechanism including a stationary cam 60 mounted on the frame of the machine. Cam followers 62 mounted on the flange 24 engage the cam 60, and through a suitable linkage system operate links 64 extending radially outward toward the collection chambers 50. The links 64 are linked to cranks mounted upon the collection chambers whereby rock shafts 66 mounted on the collection chamber are partially rotated at suitable times to operate pairs of valve cranks 68 and 70 extending in opposite directions in the direction of rotation of the forming machine. The mechanism is such that when crank 68 is rocked in one direction it will depress spring 57 to thus open valve 42 and connect the suction mold to the source of vacuum. Simultaneously therewith crank 70 is rocked in the opposite direction whereby a valve 72 is released, and the valve 72 is closed by a spring 74. The valve

72, when opened, permits the passage of air under pressure into the interior of the suction chamber through a tube 76 connected to a main pressure pipe 78, of annular form, mounted upon the wheel and connected to a source of pressure through the connection 80 and other suitable means (not shown).

The valve controlling mechanism is such that each suction mold is connected to the source of vacuum prior to its entry into the slurry, and vacuum is maintained constantly throughout the greater portion of travel of the suction mold. When the mold has traveled substantially 270° away from its deepest immersion in the slurry, the suction is cut off and air under pressure introduced thereinto, whereby the partially dried article is ejected from the surface of the mold onto a suitable removing means such as exemplified by the suction transfer head 90 and continuous belt conveyor 92. Pressure need only be applied momentarily when the transfer head 90 is in alignment with the mold, and then suction reapplied. As the mold travels from the removal conveyor position back to the slurry tank it is preferably washed by fluid forced thereagainst through spray heads 94.

It is to be appreciated that only the essential elements of the machine necessary for an understanding thereof have been herein illustrated and described, greater details being available in the above-identified application. In the above-identified application smoothing and compacting of the article is achieved by means of a resilient traveling belt, which is replaced herein by mechanism of the present invention which will now be described.

The mating die 96 of the present invention comprises a mating die element 100 matching the contours of the suction mold, projections thereon being of lesser dimensions than the depressions in the suction mold, and depressions therein being of greater dimensions than the corresponding projections of the suction mold, whereby a uniform layer of moist pulp may be interposed between the suction mold and the mating die element when they are in mating position. This layer of pulp, indicated at 102 in FIGS. 3 and 4, is rough and uneven when it emerges from the slurry, but becomes smooth and even through the action of the mating die. The mating die element comprises a peripheral, vertical flange 104 which is provided with a horizontal rim 106, speaking with reference to the general plane of the mating die element 100. The mating element is a substantially rigid, slightly flexible, impervious member of uniform thickness throughout, which may be formed of thin sheet metal or various plastic compositions, but is preferably formed of fiber glass reinforced polyethylene plastic of the type used for making boat hulls and automobile bodies. Its rigidity is such that when the peripheral rim 106 on a mating die of approximately 12 by 20 inches in outline is clamped in a rigid frame, a man may stand on it without material deflection of the central portion thereof, but its flexibility is such that it may be centrally bowed as much as one-quarter to three-eighths of an inch in either direction when fluid pressure in the order of ten to twenty pounds per square inch is applied uniformly thereto. The mating die element is mounted upon a rigid mounting plate 110 by means of a mounting frame 112 clamping the entire rim 106 to the mounting plate, such clamping being accomplished through a plurality of studs 116. The mounting plate 110 is provided with a plurality of apertures 118 whereby fluid may be introduced into or withdrawn from the space 120 between the mating die and the mounting plate. A flexible diaphragm 126 is mounted in back of the mounting plate 110, the periphery thereof being clamped to the back of the mounting plate 110 by a dish-shaped backing member 128 and a plurality of studs 130. The backing member is provided with a nipple 132 to which is clamped a hose 134. A central partition 136 in member 128 is provided with a plurality of apertures 138 whereby suction or fluid pressure may be applied to the

diaphragm 126, and when the diaphragm is withdrawn from the mounting plate 110, as illustrated in FIG. 3, it will not be subjected to extreme deformation at any one point and is limited in its outward flexing movement.

As illustrated in FIG. 3, the valve 42 is open at the instant that the mating die element is applied, and at the same time suction has been applied to the interior of the backing member 128 whereby fluid contained in the space 120 between the mating die 100 and the diaphragm 126 is partially withdrawn through the apertures 118. The vacuum applied through the valve 42 is withdrawing water from the layer of pulp but the pulp is still in a very moist condition at this instant, having just been withdrawn from the slurry. The vacuum exerted against the diaphragm 118 has caused the vertical flange 104 to give slightly inwardly and the central portion of the mating die to be bowed, or in other words, the mating die element 100 has assumed a slightly dished condition of concavity whereby the periphery of the mating die first makes contact with the periphery of the layer of pulp on the suction die. Shortly thereafter, the source of vacuum is disconnected from the mating die and air under pressure is introduced through the nipple 132, thereby causing the surface of the mating die element to progressively contact and iron the surface of the layer of pulp inwardly from its rim in all directions uniformly toward its center. The amount of fluid trapped between the mating die element and the diaphragm 126 is such that when the diaphragm 126 is forced flat against the mounting plate 110 the mating die has assumed a slightly dished condition of convexity, the peripheral portions thereof being first withdrawn from the molded pulp layer and then its surface being peeled progressively inwardly and uniformly throughout until the central portion of the mating die element alone remains in contact, whereupon the mating die element is withdrawn to a distance. It is to be appreciated that this action will not affect the layer of pulp in any fashion other than to smooth it and compact it uniformly. Suction being constantly maintained through the suction mold holds the layer of pulp in its smooth condition as the mating die is withdrawn therefrom in increment by increment.

The state of flexure of the mating die element may be reversed without departing from my invention. In other words, it may be convex when applied and concave when withdrawn.

Suitable means are provided to maintain general planes of the suction mold and mating die in parallelism during the entire application of the mating die. The means comprises a pair of mounting arms 140 extending diagonally downward beyond the slurry tank in the direction of rotation of the machine, being pivotally mounted coaxially of the machine at 142, one on each side of the wheel 10. The arms 140 extend beyond the mating die and are connected together by a crossrod 144 at their outer extremities. At each end of the mating die backing member 128 there is a longitudinally slotted radially extending arm 146, the slot 148 thereof receiving a crank pin 150. The end of the arm 146 is seated in a socket 152 at the inner end of a telescoping rod 154 slidably journaled in a tube 156 projecting inwardly from the crossrod 144 and firmly urged against the end of the arm 146 by a strong spring 158. A pin 160 mounted on the member 146 projects laterally into a slot 162 in the radial arm 140. It will be apparent from the foregoing that the mating die is thus maintained tangentially of the wheel 10, but that the spring 158 may be compressed to permit withdrawal of the mating die from the machine in order that replacements may be effected.

A shaft 170 is mounted in fixed bearings upon a suitable support 172 between arms 140 and is driven by a chain-belt drive, indicated at 174. Each end of the shaft 170 drives a disc 176 upon which a link 178 is pivotally mounted, the free end of the link 178 carrying the crank

pin 150. The arrangement is such that when the crank pin 150 is in the outer end of the slot 148, which occurs throughout the greater portion of the revolution of the disc 176, the mating die element is withdrawn from contact to a sufficient extent that the projections on the pulp article on the suction mold may approach and pass beyond the region of the mating die without being disrupted. When the link 178 is projected toward the machine, as illustrated in FIG. 3, the mating die element, 10 while still being held tangentially to the wheel, will move into contact with the pulp layer and remain in such relation while the crank pin 150 rides loosely in the slot 148 and the mating die travels with the suction mold. The lost motion connection thus provided permits the 15 close approach of the backing plate 110 as illustrated in FIG. 3 and its subsequent withdrawal as illustrated in FIG. 4, while pressure is constantly applied thereto through the spring 158. The chain drive for the disc 176 is suitably correlated with the drive means for the wheel 20 10 so that the placement and withdrawal of the mating die occurs during the time allowed.

A schematic control diagram for the actuation of the mating die is illustrated in FIG. 5 wherein it is seen that the flexible hose 134 is connected to a pair of conduits, 25 conduit 180 leading to a source of air pressure indicated at 182 and conduit 184 connected to a source of vacuum indicated at 186. A valve 188 in conduit 180 is controlled by a solenoid 190 and a valve 192 in conduit 184 is controlled by a solenoid 193. The solenoids are controlled 30 by a circuit including main line 200 which leads to a relay solenoid 202 and a contact 204 which is adapted to be engaged by a cam follower 206 engageable by a cam 208 on one of the discs 176, the contact 204 being mounted in a switch box 210 suitably mounted adjacent the disc. 35 When the cam follower 206 is down as illustrated in FIG. 5 the relay bar 212 is making contact with the branch line 214 and thus energizing solenoid 190 to open valve 188, thereby connecting the source of pressure 182 to the interior of the mating die 96 to cause outward flexing 40 of the mating die element. At this time the lower contact of the relay is open and solenoid 193 de-energized whereby valve 192 is closed. Shortly before contact of the mating die element with the layer of pulp cam follower 206 rides up on cam 208, thereby energizing relay solenoid 202 to de-energize solenoid 190 while energizing solenoid 193, thus disconnecting the source of pressure and connecting the vacuum source to the mating die whereby the mating die element assumes its position of 50 concavity immediately preceding contact with the layer of pulp. Shortly thereafter the vacuum is cut off and pressure is reapplied while the mating die element is in contact with the pulp.

It is to be appreciated that cam 208 could be interrupted whereby a series of reversals of the mating die element from concavity to convexity would be accomplished during the time that contact is maintained, thereby causing a series of hammer blows to be applied to the layer of pulp. However, I have been unable to ascertain any improvement in quality thus achieved, the one reversal 60 being sufficient to achieve a smooth surfaced, compacted article.

The upper half of the forming wheel is surmounted by a hood 220 which is spaced from the surface of the wheel to allow free flow of air between the hood and the 65 wheel. The hood is heavily insulated as indicated at 222 and is provided with a reflective lining 224 in back of a plurality of radiant heating elements 226. Thus the smoothened and compacted layer of pulp is not only subjected to radiant, drying heat but is constantly being 70 traversed by a stream of heated drying air whereby moisture and steam is rapidly conveyed away from the pulp through the collection chambers. A sufficient degree of rigidity is thus imparted to the pulp article that it may be safely blown from the forming mold onto the transfer mechanism 90 and then dropped onto the con-

veyor belt 92 without being torn or dented. The conveyor belt 92 preferably conveys the articles through a drying oven for complete drying prior to stacking or other handling.

Having illustrated and described a preferred embodiment of the machine and the method of pulp forming involved, I claim as my invention all such modifications in detail and arrangement which come within the true spirit and scope of the following claims:

I claim:

1. The method of manufacturing a molded pulp article having all portions thereof adjacent a general plane, which process comprises sucking a layer of pulp onto a suction mold providing a foraminous mold surface having a corresponding general plane by applying suction through said surface while said mold is immersed in a pulp slurry, withdrawing said mold and layer from said slurry, pressing an impervious slightly flexible mating die element providing a smoothing surface having a corresponding general plane against said layer on said mold surface immediately after said mold has been withdrawn from said slurry and while maintaining said suction, bowing said die element to a slightly dished condition to bow said smoothing surface in one direction from its general plane prior to pressing said mating die against said layer and then bowing said die element to an opposite slightly dished condition to bow said smoothing surface from its general plane in an opposite direction while in contact with said layer and while the general planes of said surfaces are maintained parallel so that said smoothing surface is progressively moved in opposed directions into contact with said layer and is then progressively peeled in opposed directions from said layer, and withdrawing said die element from contact with said layer while continuing to maintain said suction.

2. The method of manufacturing a molded pulp article having all portions thereof adjacent a general plane, which process comprises sucking a layer of pulp onto a suction mold providing a foraminous mold surface having a corresponding general plane by applying suction through said surface while said mold is immersed in a pulp slurry, withdrawing said mold and layer from said slurry, pressing an impervious slightly flexible mating die element providing a smoothing surface having a corresponding general plane against said layer on said mold surface immediately after said mold has been withdrawn from said slurry and while maintaining said suction, bowing said die element in one direction to bow said smoothing surface from its general plane to a slightly convex condition prior to pressing said mating die against said layer and then bowing said die element in an opposite direction to bow said smoothing surface from its general plane to a slightly concave condition while in contact with said layer and while the general planes of said surfaces are maintained parallel so that said smoothing surface is progressively moved in opposed directions into contact with said layer and is then progressively peeled in opposed directions from said layer, and withdrawing said die element from contact with said layer while continuing to maintain said suction.

3. The method of manufacturing a molded pulp article having all portions thereof adjacent a general plane, which process comprises sucking a layer of pulp onto a suction mold providing a foraminous mold surface having a corresponding general plane by applying suction through said surface while said mold is immersed in a pulp slurry, withdrawing said mold and layer from said slurry, pressing an impervious slightly flexible mating die element providing a smoothing surface having a corresponding general plane against said layer on said mold surface immediately after said mold has been withdrawn from said slurry and while maintaining said suction, bowing said die element in one direction to bow said smoothing surface from its general plane to a slightly concave condition prior to pressing said mating die against said layer and then bowing said die element in an opposite direction to bow said

smoothing surface from its general plane to a slightly convex condition while in contact with said layer and while the general planes of said surfaces are maintained parallel so that said smoothing surface is progressively moved in opposed directions into contact with said layer and is then progressively peeled in opposed directions from said layer, and withdrawing said die element from said layer while continuing to maintain said suction.

4. The method of manufacturing a molded pulp article having all portions thereof adjacent a general plane, which process comprises sucking a layer of pulp onto a suction mold providing a foraminous mold surface having a corresponding general plane by applying suction through said surface while said mold is immersed in a pulp slurry, withdrawing said mold and layer from said slurry, pressing an impervious slightly flexible mating die element providing a smoothing surface having a corresponding general plane against said layer on said mold surface immediately after said mold has been withdrawn from said slurry and while maintaining said suction, bowing said die element to a slightly dished condition to bow said smoothing surface in one direction from its general plane prior to pressing said mating die against said layer and then bowing said die element to an opposite slightly dished condition to bow said smoothing surface from its general plane in an opposite direction while in contact with said layer and while the general planes of said surfaces are maintained parallel so that said smoothing surface is progressively moved in opposed directions into contact with said layer and is then progressively peeled in opposed directions from said layer, withdrawing said die element from said layer while continuing to maintain said suction, then drying said layer on said mold while continuing to maintain said suction until said layer is substantially dry, and then removing the resulting article from said mold.

5. In a pulp molding mechanism including a suction mold providing a rigid foraminous mold surface having all portions thereof adjacent a general plane, a container for pulp slurry, means to immerse said surface of said mold in said slurry and to withdraw said surface from said slurry, means for applying suction through said surface while said surface is immersed in and withdrawn from said slurry to deposit a layer of pulp on said surface and to withdraw said layer from said slurry with a layer of pulp on said surface, the improvement which comprises, a slightly flexible and impervious mating die element providing a smoothing surface having a corresponding general plane, means for pressing said die element into contact with said layer and for maintaining the general planes of said surfaces parallel during said pressing, and means for bowing said element in one direction into a slightly dished condition prior to said contact and for then bowing said element in an opposite direction into an oppositely dished condition during said pressing to progressively move said smoothing surface in opposed directions into pressing contact with said layer and to then progressively peel said smoothing surface in opposed directions from said layer, said suction means maintaining said suction during contact of said element with said layer.

6. In a pulp molding mechanism including a suction mold providing a rigid foraminous mold surface having all portions thereof adjacent a general plane, a container for pulp slurry, means to immerse said surface of said mold in said slurry and to withdraw said surface from said slurry, means for applying suction through said surface while said surface is immersed in and withdrawn from said slurry to deposit a layer of pulp on said surface and to withdraw said layer from said slurry on said surface, the improvement which comprises a slightly flexible and impervious mating die element providing a smoothing surface having a corresponding general plane, means for pressing said die element into contact with said layer and for maintaining the general planes of said surfaces parallel during said pressing, means for bowing said element in one direction into a slightly dished condition prior to

said contact and for then bowing said element in an opposite direction into an oppositely dished condition during said pressing to progressively move said smoothing surface in opposed directions into pressing contact with said layer and to then progressively peel said smoothing surface in opposed directions from said layer, said suction means maintaining said suction during contact of said element with said layer, said means for bowing said element including a casing having edge portions secured to the edges of said element in sealing relationship therewith and a bottom wall spaced from said element to provide a fluid chamber, and means for varying the pressure of the fluid within said chamber in opposite directions.
